UNITED STATES PATENT OFFICE.

WILLIAM J. PHELAN, OF NEW SALEM, PENNSYLVANIA.

SAFETY-LOCK FOR SELF-DUMPING MINE-CAGES.

1,085,297.

Specification of Letters Patent. Patented Jan. 27, 1914.

Application filed April 12, 1913. Serial No. 760,734.

To all whom it may concern:

Be it known that I, WILLIAM J. PHELAN, a citizen of the United States, and resident of New Salem, in the county of Fayette 5 and State of Pennsylvania, have invented certain new and useful Improvements in Safety-Locks for Self-Dumping Mine-Cages, of which the following is a specification.

My invention relates to the class of self-dumping mine cages in which, when hoisted to the top of the mine shaft in which they are erected, the mine cages are automatically caused to tilt or dump in order to discharge materials loaded in mine cars positioned on 15 the cage platforms, and the invention more particularly relates to the construction and arrangement of a self-dumping mine cage having novel means whereby the platform of the mine cage is locked in hoisting position and the possibility of premature tipping or dumping of the cage platform is prevented and overcome.

Heretofore, with self-dumping mine cages of the class to which this invention relates, 25 the tilting platform of the dumping cage is normally prevented from turning or tilting during the hoisting operations by means of guiding shoes attached to and forming a part of the mine cage, the shoes engaging 30 with the wooden guides extending vertically from the bottom to the top, and for some distance above the top of the shaft, on opposite ends of the mine shaft. With such constructions, should the shaft guides, which 35 ordinarily are made of wood, become broken, the guiding shoes become inoperative and in this way occasion great liability of the cage platform dumping or tilting during the hoisting or lowering operations, upon reaching 40 a broken point in the length of the shaft guides and thereby spilling and endangering the freight being carried on the platform of the cage, whether men or material.

One object of my invention is to provide 45 a hoisting cage having novel means whereby dumping or tilting of the mine cage platform during the hoisting and lowering operations is prevented in all positions of the cage in the mine shaft, except such as those 50 at which tipping means are provided for mechanically dumping the mine cage platform, and the possibility of accident is avoided and overcome.

Another object of this invention is to provide a safety lock for mine cages whereby

dumping or tilting of the mine cage platform is prevented, and by having novel means whereby the safety lock is actuated to release the locking mechanism at predetermined positions in or above the top of 60 the mine shaft.

A still further object of the invention is to provide a mine hoist having improved means whereby the cage platform is actuated to tilt or dump at the desired 65 points in the mine shaft.

Still further objects of my invention will appear hereinafter as the invention is more fully described and claimed.

Referring to the drawings, forming part 70 of this specification, Figure 1 is a plan showing a mine shaft having a tilting hoisting cage operatively mounted therein and constructed and arranged in accordance with my invention. Fig. 2 is a side elevation of 75 the hoisting cage showing the tilting cage platform and, in dotted lines, the platform in tilted position, as constructed in accordance with this invention. Fig. 3 is a sectional plan on a larger scale, showing a detail 80 of the guiding shoes by which tilting or dumping of the cage platform is avoided and prevented during the cage hoisting operations. Fig. 4 is a side elevation showing the construction and arrangement of the 85 locking pins and connecting mechanism forming part of this invention by which the mine cage platform is locked or secured in hoisting position during the cage hoisting operations. Fig. 5 is a similar side elevation 90 showing the means whereby the locking pins are actuated to release the mine cage upon reaching its dumping position within or above the top or mouth of the mine shaft.

In the accompanying drawings, the numeral 2 designates a mine shaft having vertically extending wooden guides 3, 3, positioned on opposite sides of the shaft, which extend from top to bottom of the mine shaft, 100 and by which the tipping mine cage platform is maintained in hoisting position within the shaft 2.

The cage is provided with a main frame comprising vertical members or posts 4, 4, 105 and a cross bar or beam 5 by which the cage is suspended from the clevis 6 which is detachably secured to the end of the hoisting cable or ropes of the hoisting mechanism.

Pivoted to the bottom of the posts or ver- 110

tical members 4, 4, of the main frame is a cage platform 7 having vertical posts or side members 8, 8, connected at their upper ends by a horizontal bar or shaft 9, and mounted on the ends of the shaft 9 are flanged guide wheels 10, 10. The upper surface of the tilting platform 7 is provided with track rails 11, 11, and with openings or slots 12, 12, in the bottom thereof for the wheels 13 of mine cars 14. The ends of the mine cars 14 have tilting doors 15 hinged at their upper edges to the sides of the mine cars, and a latch to retain the doors in closed position until released, the lower ends of the doors being arranged, when released, to swing outwardly and permit materials loaded in the mine cars 14 to be dumped or discharged therefrom when the platform 7 is inclined or in dumping position, or that shown in dotted lines in Fig. 2 of the drawings.

Located at the top of the mine shaft 2 on each side thereof, in position to be engaged by the guide wheels 10, 10, on the ends of the shaft 9, which is secured to the upper ends of the upright members 8, 8, of the tilting platform 7, are curved guides 16, 16, forming a track and the continuity of the vertical shaft guides 3 is interrupted by gaps or openings 17 so as to clear the guiding shoes 18 which are connected by the curved arms 19 to the vertical members of the tilting platform 7 and permit the track formed by the curved guides 16 to engage with the guide rollers 9, and by engagement with these rollers cause the platform 7 to tilt or dump upon reaching the top of the mine shaft. The guide shoes 18 are arranged to pass through the gaps 17 in the guides 3 when the cage platform 7 is moving into its tilting or dumping position, and in being returned to its horizontal position, at the beginning of the cage lowering operation.

Fastened to the cross beam 5 on the upper portion of the platform frame are brackets 20 in which the horizontal locking pins 21 are mounted and arranged to move axially or lengthwise, so that the free ends of the pins 21, when advanced, will engage with the side members or posts 8, 8, of the platform frame and by engagement therewith lock the tilting platform 7 in its horizontal or hoisting position. The inner ends of the locking pins 21 are connected to levers 22 and 23 which are keyed or otherwise rigidly secured on the shafts 24 and 25. At an intermediate point in its length the lever 23 is keyed or otherwise fastened to the shaft 25, and the upper end of the lever 23 is connected by a link 26 to the lower swinging end of the lever 22 so as to provide means which will insure the pins 21, 21, traveling in unison and the same relative distance when being advanced and withdrawn or moved into or out of locking position.

The shafts 24 and 25 are mounted in bearings 24^a, 25^a, and extend transversely across the top of the cross beam 5 of the platform frame, and levers 27 and 28 are keyed to the ends thereof. The lower ends of the levers 27 and 28 are pivoted to one end of sliding links or rods 29 and 30, the opposite ends of these links being pivotally connected to the shoes 31 and 32, and the shoes 31 and 32 are also pivotally connected by pins 33 to the upper ends of the uprights or posts 8, 8, on the frame forming part of the tilting platform 6.

The adjacent overlapping ends of the links or rods 29 and 30 have collars or shoulders 34 thereon and the reduced overlapping ends of these rods project through an opening in the bracket 35 which is secured to the top of the platform 7. The ends of the helical springs 36 on the rods 29 and 30 engage with the bracket 35, and the collars 34, so as to move each its rod 29 or 30 in one direction or outwardly and maintain the shoes 31 and 32 in contact with the slides 37, 37. The springs 36, when extended to hold the shoes 30 and 32 in engagement with the slides also operate through the medium of the levers 27 and 29, the shafts 24 and 25, and the levers 22 and 23, to cause the pins 21, 21, to be extended in the bracket bearings 20 and maintain the free ends of these pins in locking engagement with the uprights 8, 8, so that the platform 7 cannot tilt with respect to the posts 4, 4, of the frame of the hoist while the pins 21 are in this position.

The guides 37 are provided with curved shoe engaging faces 38 so that when the cage reaches the upper end of the shaft 2 the shoes 31, 32, will engage the curved faces 37 and be moved inwardly, and, through the connecting mechanism, cause the pins 21 to retract or move inwardly so as to disengage the platform 7 from the frame and permit the curved track 16, by engagement with the guide wheels 10, to move the tilting platform 7 from the position shown in full lines into that shown in dotted lines in Fig. 2, while the cage platform is being lifted sufficiently to move the guide wheels 10 from the position shown in full lines in Fig. 2 into that shown by dotted lines in this figure.

The track rails 11, 11, on the platform 7 of the mine cage are cut away so as to provide the recesses 12, 12 and at the bottom of the mine shaft permanently secured track rails are provided which enter these recesses and align with the ends of the track rails 11, 11, when the cage platform is in its lowermost position at the bottom of the shaft 2, the loaded mine car 14 being pushed upon the platform 7 so the mine car wheels will rest upon the portions of the track rails projecting upwardly within the recesses 12, 12.

The operation of my improved apparatus

is as follows: The hoisting cage is lifted in the usual manner and during the lifting operations, tilting of the platform 7 is prevented by engagement of the guiding shoes 18, 18, with the vertical guides 3, 3. During the hoisting movement of the mine cage the lock operating shoes 31 and 32 are extended in the position shown in Fig. 4 by the helical springs 36, 36, and, when in this position the locking pins 21, 21, which are operatively connected with the shoes 31 and 32 are held in locking position by the action of the springs so as to fasten the tilting platform 7 against tilting movement. When at the top 15 of the shaft, as the cage platform reaches the position relative to the curved guides 16 shown in full lines in Fig. 2, the tilting wheels 10, 10, engage with the guides 16 and further lifting movement of the mine cage 20 causes the platform 7 to be tilted into the position shown in dotted lines in Fig. 2. The gaps 17 interrupting the continuity of the guides 3 at the top of the shaft 2 permit the guiding shoes 18 to move transversely from 25 one side to the other of the guides 3, and, as the guide wheels 10 approach the lower end 30 of the curved guide tracks 16 the operating surfaces 38 of the guides 37, 37, and by such engagement the shoes 31 and 32 are caused to move toward each other so as to compress the springs 36, 36. When the 35 shoes 31, 32 are moved inwardly in this manner the levers 27 and 28, shafts 24 and 25, and the links 22 and 23 retract or move the locking pins 21 inwardly so as to release the 40 platform 7 and permit the free dumping movement of the platform 7 and the mine car 14 thereon, by the curved guide track 16. As the mine cage starts upward from the bottom of the mine shaft the face of the platform 7 is moved toward the bottom of the mine car 14 and the mine car wheels 13 45 enter the openings or recesses 12 in the platform 7 so that the mine car 15 is in this way secured in position on the platform and will not slide forwardly thereon later when at the top of the mine shaft the platform is 50 tilted to empty the mine car 15 of its contents. After tilting the platform the movement is reversed and the cage again lowered into the mine shaft 2. At the beginning of such reverse or lowering movement the 55 curved guides 16, by engaging the guide wheels 10, 10, cause the cage platform 7 to first assume its horizontal position, and further downward movement of the cage removes the shoes 31 and 32 from engagement 60 with the curved faces 38 of the guides 37 so that the springs 36 are free to extend, and, through the medium of the connecting lever mechanism, operate to advance the locking pins 21 into position to again fasten the 65 platform in horizontal position on the frame of the mine cage. In lowering the mine cage the shoes 18, 18, again pass through the gaps 17 in the guides 3, and, when further lowered in the shaft, again engage with the sides of the guides 3. The above described 70 operations are then repeated with the successive hoist raising and lowering operations.

The advantages of my invention will be apparent to those skilled in the art. The 75 provision of the locking pins prevents accidental tipping or tilting of the cage platform in case of breakage or other accident to the guides which would render the guide shoe inoperative and the possibility of spilling the load on the cage into the shaft is overcome and prevented. The locking pins are automatically caused to move into and out of locking position as the mine cage reaches and moves away from the dumping 80 position of the cage.

Modifications in the construction and arrangement of the parts may be made without departing from my invention as defined in the appended claims. 90

I claim:

1. A dumping mine cage comprising a cage frame, a dumping platform pivoted thereto, and locking means on the said frame engaging with hand fastening the platform 95 in hoisting position thereon during the cage hoisting operations and unlocking means operatively connected with said locking means, said locking means being arranged to be disengaged when the mine cage reaches its 100 dumping position in each hoisting operation.
2. A dumping mine cage comprising a cage frame, a dumping platform pivoted thereto, and locking means on the said frame 105 engaging with and fastening the platform in hoisting position thereon during the cage hoisting operations, said locking means comprising locking pins slidably mounted on the cage frame, helical springs to extend the pins into locking engagement with the dumping platform, and shoes pivotally mounted on the cage frame and operatively connected to the locking pins to retract the pins and permit tilting the dumping platform at predetermined positions in the lifting movement of the mine cage. 110
3. A dumping mine cage comprising in combination a cage frame, a dumping platform pivoted thereto, locking pins slidably 120 mounted on the platform arranged to engage the cage frame and lock the platform in hoisting position thereon during the hoisting operations, pivoted shoes for actuating the locking pins to release the platform, and means arranged to engage said shoes to move the pins into disengaged position at the end of each cage hoisting operation. 125
4. In a self-dumping mine cage, the com- 130

- bination with a mine shaft having cage guides therein of a hoisting cage frame having a dumping platform pivoted thereto, means at the top of the mine shaft for mechanically dumping said platform, means connected to the platform engaging with the cage guides to prevent dumping of the platform in the mine shaft, a lock connected to said frame and arranged to fasten the platform thereto during the hoisting operations, and means embodying pivoted shoes operatively connected with said lock for releasing said lock when the cage reaches its dumping position.
- 5 5. In a self-dumping mine cage, the combination with a hoisting cage frame having a dumping platform pivotally mounted thereon and means for normally preventing dumping of the platform during the hoisting operations, of locking means on the cage frame whereby the platform is fastened to the frame and dumping thereof prevented during the hoisting operations, and means embodying pivoted shoes operatively connected with the locking means, and co-operating means positioned at the top of the mine shaft for mechanically releasing the locking means and dumping said platform.
- 10 6. In a self-dumping mine cage, the combination with a hoisting cage frame having a dumping platform pivotally mounted thereon and means for normally preventing dumping of the platform during the hoisting operations, of locking means on the cage frame whereby the platform is fastened to 25 the frame and dumping thereof prevented during the hoisting operations, and means embodying pivoted members operatively connected with the locking means for releasing the locking means at predetermined positions in the lifting movement of the mine cage.
- 15 7. In a self-dumping mine cage, the combination with a hoisting cage frame having a dumping platform pivotally mounted thereon and means for normally preventing dumping of the platform during the hoisting operations, of locking means on the cage frame whereby the platform is fastened to the frame and dumping thereof prevented during the hoisting operations, said locking means comprising locking pins slidably mounted on the cage frame, helical springs to extend the pins into locking engagement with the dumping platform, and 30 shoes pivotally mounted on the cage frame and operatively connected to the locking pins to retract the pins and permit tilting the dumping platform at predetermined positions in the lifting movement of the mine cage.
- 15 8. In a self-dumping mine cage, the combination with a hoisting cage frame having a dumping platform pivotally mounted thereon and means for normally preventing dumping of the platform during the hoisting operations, of locking means on the cage frame whereby the platform is fastened to 35 the frame and dumping thereof prevented during the hoisting operations, and means embodying pivoted members operatively connected with the locking means for releasing the locking means at predetermined 40 positions in the lifting movement of the mine cage.
- 15 9. In a self-dumping mine cage, the combination with a hoisting cage frame having a dumping platform pivotally mounted thereon and means for normally preventing dumping of the platform during the hoisting operations, of locking means on the cage frame whereby the platform is fastened to the frame and dumping thereof prevented during the hoisting operations, said locking means comprising locking pins slidably mounted on the cage frame, helical springs to extend the pins into locking engagement with the dumping platform, and 45 shoes pivotally mounted on the cage frame and operatively connected to the locking pins to retract the pins and permit tilting the dumping platform at predetermined 50 positions in the lifting movement of the mine cage.
- 15 10. In a self-dumping mine cage, the combination with a hoisting cage frame having a dumping platform pivotally mounted thereon and means for normally preventing dumping of the platform during the hoisting operations, of locking means on the cage frame whereby the platform is fastened to 55 the frame and dumping thereof prevented during the hoisting operations, said locking means comprising locking pins slidably mounted on the cage frame, helical springs to extend the pins into locking engagement with the dumping platform, and shoes pivotally mounted on the cage frame and operatively connected to the locking pins to retract the pins and permit tilting the dumping platform at predetermined positions in the lifting movement of the mine cage.

Signed by me at Uniontown, Pa. this 22 day of March 1913.
